UNITED STATES PATENT OFFICE.

MORTIMER HOWARD FARMER, OF VIRDEN, ILLINOIS.

LOCK.

960,868.

Patented June 7, 1910.

Application filed December 18, 1908. Serial No. 468,101.

To all whom it may concern:

Be it known that I, MORTIMER HOWARD FARMER, a citizen of the United States, and a resident of Virden, in the county of Ma-
5 coupin and State of Illinois, have made cer-
tain new and useful Improvements in Locks,
of which the following is a specification.

My invention relates to improvements in
spring locks and it consists in the combina-
10 tions, constructions and arrangements here-
in described and claimed.

An object of my invention is to provide a
simple form of locking mechanism which
may act in the manner of an ordinary spring
15 lock until the door or other swinging mem-
ber to which it is applied is shut, when the
lock will immediately become "dead" and
will require a key to unlock it.

A further object of my invention is to
20 provide novel means for rendering the latch
bolt immovable against the application of
instruments, such as a chisel or other de-
vice, which will be sufficient to force the
latch bolt of an ordinary spring lock back
25 with ease.

Other objects and advantages will appear
in the following specification and the novel
features of the invention will be particularly
30 pointed out in the appended claims.

My invention is illustrated in the accom-
panying drawings, in which—

Figure 1 is a plan view of the device
showing the locking mechanism in its nor-
mal position, the upper plate being removed.
35 Fig. 2 is a similar view showing the latch
bolt in its retracted position. Fig. 3 is a
longitudinal section through the device.
Fig. 4 is a top view of the bottom plate.
Fig. 5 is a section along the line 5—5 of
40 Fig. 1. Fig. 6 is a section along the line
6—6 of Fig. 1. Fig. 7 is a perspective view
of the key and the push cams. Fig. 8 is a
perspective view of the guard plate.

Referring now particularly to Fig. 3 I
45 have shown therein a metal casing consisting
of a main portion A and a bottom portion B.
The casing is divided by a transverse parti-
tion C having a slot c. Projecting through
the forward part of the casing is the latch
50 bolt D. This is provided with the longi-
tudinal dove-tailed slot d, as clearly shown
in Fig. 6. Secured to the rear end of the
latch bolt is a guide rod E, about which is
coiled a spiral spring F. The guide rod E
55 extends through an opening in the partition

C and is rigidly secured to the central por-
tion of a U-shaped member G, the latter be-
ing for the purpose of operating the latch
bolt and limiting its movement in either di-
rection.

The guard plate H is shown in Fig. 8. It
is preferably made of a single piece of metal
stamped in the form shown and is provided
with a rectangular slot h, an upturned
flange h' at its end and a smaller upturned
flange h² between the slot h and the flange
h'. The oppositely inclined flanges h³ are
arranged to enter the slot d of the latch
bolt D, as clearly shown in Fig. 6.

In Fig. 7 I have shown the push cams for
operating the latch bolt after the door is
shut. These push cams consist of a pair of
members J and K, each provided with the
curved arms j and k, respectively. In the
figure I have shown the members J and K
as being permanently secured to a spindle
L. The push cam K is provided with a
laterally projecting wing k⁴ having a central
curved portion k⁵. The spindle L projects
through a key hole in the casing A and push
cams J and K are arranged respectively
above and below the U-shaped member G.
The arms j and k are bent inwardly to en-
gage the enlarged ends g and g' of the mem-
ber G.

Pivottally supported on the partition C is
a latch plate P whose end extends under-
neath the curved portion k⁵ of the cam
member K in the normal position of the
latter. The end p of the plate P is turned
90 outwardly so as to be engaged by the cam
wings k⁴ of the push cam K. The opposite
end of the latch plate is provided with an
inwardly projecting stop p², which is ar-
ranged to engage the rear end of the guard
plate H, as shown in the drawings.

The removable plate B is provided with a
spring S which normally keeps the guard
plate H in its forward position by the en-
gagement of the flange h². The leaf spring
100 R, attached to the plate B, bears upon the
latch plate P to hold the latter normally in
line with the latch bolt D. The pins T
serve the purpose of guide members for the
latch plate P when the parts are assembled.

From the foregoing description of the
various parts of the device the operation
thereof may be readily understood. When
the parts A and B are in their assembled
110 position, the guard plate H is forced to the

front as shown in Fig. 1, but both the plate H and the latch bolt D may be forced inwardly, the former against the tension of its spring S and the latter against the tension 5 of the spiral spring F. Thus, when the latch bolt comes into contact with the strike plate on the door frame, both of these members are forced inwardly. It will be observed that in the normal position of the guard 10 plate H its rear end h⁵ engages the curved cam surface p³ of the latch plate P, thereby forcing the latter into the position shown in dotted lines in Fig. 3, in which it will be seen that the stop p² is out of the way of the 15 latch bolt D, thereby permitting the latter to be forced inwardly. When the door is closed, however, the latch bolt springs back into position, thereby locking the door while the plate H remains in its shifted position, 20 being held there by one side of the strike plate which presses against the flange h', see Fig. 3. This forces the latch plate into the position shown in Fig. 2. Just as soon as the rear end h⁵ of the guard plate leaves 25 the cam portion p³, the latch plate P is forced inwardly by means of the spring R, the stop p² entering the slot h of the guard plate H and taking the position immediately behind the latch bolt D, as shown in Fig. 3. The 30 lock is now "dead" and cannot be opened except by means of the spindle L. When the spindle L is turned the cam wings k⁴ first engage the outwardly turned end p of the latch plate P, thereby forcing the latter 35 inwardly when the stop p² will be thrown out of engagement with the latch bolt D. On further movement of the key one of the arms k and j will come into contact with the arms of the member G, thereby forcing the 40 latter to the rear and drawing with it the latch bolt and the guard plate H. The position of the mechanism when the door is being unlocked is shown in Fig. 2. After the door is opened the key releases the guard 45 plate H and the latch bolt D assumes the position shown in Fig. 1.

I am aware that devices have been made in which the dead locking of the bolt has

been accomplished and I do not claim broadly such a device, but

50

What I claim is—

1. The combination with a strike plate provided with an opening, of a spring actuated latch bolt, a slotted guard plate slidably mounted on said latch bolt, a spring 55 actuated latch plate having a stop adapted to project through the slot in said guard plate into the path of the latch bolt.

2. The combination with a strike plate provided with an opening, of a spring actuated latch bolt, a slotted guard plate slidably mounted on said latch bolt, a spring actuated latch plate provided with a cam adapted to engage said guard plate, a stop on said latch plate adapted to project through the 60 slot in said guard plate, said stop being held normally out of the path of said latch bolt by the engagement of the guard plate with the cam on the latch plate and permitted to spring into the path of the bolt through a 65 movement of said guard plate.

3. A lock comprising a casing, a spring-actuated latch bolt adapted to reciprocate in said casing and provided with a slot, a slotted guard plate arranged to reciprocate 75 in the slot in said bolt, a pivoted stop having a cam portion normally in engagement with the rear end of said guard plate but adapted to enter within the slot in said guard plate when the latter is moved, thereby bringing 80 said stop into the path of the latch bolt, a cam member having a central curved portion and laterally extending cam wings arranged to engage the rear end of said pivoted stop to raise the latter out of engagement with said latch bolt, integral curved arms carried by said cam member, a U-shaped sliding plate attached to said bolt, and a spindle adapted to enter a slot in said 85 cam member to force said arms into engagement with said U-shaped sliding piece for retracting the bolt.

MORTIMER HOWARD FARMER.
